UNITED STATES PATENT OFFICE.

WILLIAM H. HARTMAN, OF LOS ANGELES, CALIFORNIA, ASSIGNOR TO RANDALL CONTROL AND HYDROMETRIC CORPORATION, OF LOS ANGELES, CALIFORNIA, A CORPORATION OF CALIFORNIA.

HYDRAULIC-ELEVATOR-CONTROL SYSTEM.

Application filed December 15, 1920, Serial No. 431,026. Renewed June 26, 1923.

To all whom it may concern:

Be it known that I, WILLIAM H. HARTMAN, a citizen of the United States, and a resident of Los Angeles, county of Los Angeles, and State of California, have invented a certain new and useful Hydraulic-Elevator-Control System, of which the following is a specification.

The invention relates to elevator control systems and particularly to control systems for hydraulic elevators.

An object of the invention is to provide means for preventing creeping of the elevator car, due to leaky valves or other causes, when an elevator shaft door is unlocked or open.

Another object of the invention is to provide means operatively by the unlocking or opening of a shaft door for throwing the control mechanism into operation.

Another object of the invention is to provide control means normally disengaged from the car operating lever which is brought into engagement with the lever simultaneously with the actuation of the control means.

The invention possesses other advantageous features, some of which, with the foregoing, will be set forth at length in the following description, where I shall outline in full, that form of the invention which I have selected for illustration in the drawings accompanying and forming part of the present specification. In said drawings, I have shown one embodiment of the invention, but it is to be understood that I do not limit myself to such form, since the invention, as expressed in the claims, may be embodied in a plurality of forms.

Difficulty is experienced in the operation of hydraulic elevators due to the creeping of the elevator car when the control lever is in neutral position, which creeping is usually caused by leaky valves in the hydraulic motor. This difficulty is particularly noticeable when the car is brought to rest at a floor. Means have been proposed for moving the control lever of the motor from neutral position in a direction to counteract the creeping of the car, and thereby hold the car substantially stationary. These proposed means have been permanently connected with the control lever so that they must be continuously moved by

the control lever, during the normal operation of the car. This has imposed a heavy load on the control lever, making it rather difficult to move and making the operation of the elevator an arduous task. In accordance with my invention, the control means is normally disconnected from the control lever so that the lever is handled with facility and is brought into engagement with the control lever when the car has been stopped at a floor and the shaft door opened, and is disengaged when the shaft door is closed.

Referring to the drawings:

Figure 1 is a diagrammatic representation of an elevator car equipped with my invention, disposed in an elevator shaft opposite a shaft door.

Fig. 2 is an elevation of the stationary wire engaging device.

Fig. 3 is a vertical section through the stationary wire engaging device.

The present invention relates to hydraulic elevators and provides means for preventing the creeping of the elevator car due to leaky valves in the hydraulic motor when the car is halted at a floor and the shaft door opened. The elevator car 2 is provided with a control lever 3 secured to the shaft 4, which is operatively connected with the valves on the hydraulic motor, movement of the lever to one side of the neutral position serving to operate the valves to cause the car to ascend and movement to the other side serving to operate the valves to cause the car to descend. When the valves are leaky, the car tends to move either upward or downward, when the control lever is in neutral position, and means are provided for moving the control lever slightly from neutral position in a direction to counteract the creeping movement of the car. Arranged in the elevator shaft is a vertically disposed stationary wire or cable 5, which is normally slidably engaged by a carriage 6 carried by the elevator car and when a shaft door is opened, the carriage is clamped to the wire, so that movement of the car produces a movement of the carriage with respect to the car and this movement is employed to move the control lever to stop the movement of the car. Depending from the car are a pair of vertical guides 7 upon which the vertically movable

carriage is disposed, the carriage being provided with rollers 8, engaging the guides. Arranged in the carriage is a cylinder 9 having a spring pressed piston 12 therein, to which is secured the piston rod 13. Secured to the outer end of the piston rod is a shoe 14 which is adapted to be moved to clamp the cable 5 to the carriage. The carriage is formed in two parts lying on opposite sides of the cable, the part 15 being provided with rollers 16 engaging the cable. The piston operates to clamp the cable between the shoe 14 and the carriage part 15, thus holding the carriage stationary in the shaft. The piston is operated by fluid under pressure, conveyed to the car through the flexible conduit 17 to the three-way valve 18, which is operated by the opening and closing of the shaft door 19. Secured to the valve lever is rod 21 which is connected to the cam-shoe 22 pivotally mounted on the elevator car. Lateral movement of the shoe 22 causes vertical movement of the rod 21. Mounted in the shaft at each door, 25 is a bell crank lever 23 having a projection 24 adapted to be engaged by the cam-shoe 22 when the car is opposite a floor. The other end of the lever 23 carries a roller 25 which cooperates with a cam-slide 26 secured to the shaft door. The slide 26 has a depressed end on which the roller 25 rests when the door is closed, and a body portion on which the roller rests when the door is open partially or fully. When the door is 30 opened, therefore, the shoe 22 is depressed and the valve 18 operated to admit air to the cylinder 9 and clamp the carriage to the cable. When the door is closed, the valve is operated to exhaust the air through the muffler 27, releasing the carriage from the cable.

Movement of the carriage with respect to the car, causes a movement of the controller lever and means are provided for connecting 35 the carriage and the controller lever only when a shaft door is open, so that the weight of the carriage will not always be imposed on the controller lever. Secured to the shaft 4 is an arm 31 provided on its end with a segmental gear 32. The carriage is suspended from a lever 33, pivoted to the car at 34 and normally aligned with the arm 31. The lever 33 is provided on its end adjacent the segmental gear 32, with a segmental gear 35, which is slidable into and out of mesh with the segmental gear 32. The gear 35 is mounted on a slide 36, connected to the piston rod 37, of a spring returned piston 38 disposed in the cylinder 39 mounted 40 on the lever 33. The piston is operated by air under pressure conducted from a suitable source by pipe 43, which air is admitted to and released from the cylinder by the valve 18, simultaneously with the admission 45 and release of air from the cylinder 9.

When the segmental gears are in engagement, the carriage is connected to the controller lever so that movement of the carriage with respect to the car moves the controller lever and this engagement is established only when a shaft door is open. When the gears are separated, there is no additional load on the controller lever. The weight of the carriage is counterbalanced by the weight 41 secured to the lever 42, 70 fulcrumed on the car and pivoted to the lever 33.

The operation of the device may be now briefly explained. When the car stops at a landing, the operating lever 3 is in neutral position, and gears 32 and 35 are disengaged. However, upon opening of door 19, the rod 21 is operated, admitting air to cylinders 9 and 39. This serves to clamp the carriage 6 to its guide, and to cause engagement of gears 32 and 35. Upon creeping of the car in either direction, a slight rotation is imparted to lever 33 about the pivot on carriage 6, and gear 35 fixed to this lever imparts rotation to gear 32 and to the operating shaft 4. This rotation is in the proper direction to stop the movement of the car.

I claim:

1. In an elevator system having a car operating in the shaft, means for controlling the movement of the car, a member carried by the car but relatively movable therewith, for operating the controlling means in response to movement of the car, and means for mechanically connecting and disconnecting said member and the operating means.
2. In an elevator system having a car operating in a shaft and a door for the shaft, means for controlling the movement of the car, a member carried by the car for operating the controlling means, means responsive to the opening of the door for maintaining said member stationary with respect to the shaft, and means for mechanically connecting and disconnecting said member and the operating means.
3. The combination with an elevator shaft provided with a door, of an elevator car in said shaft, means for controlling the movement of said car, a movable carriage on said car operably associated with and normally disconnected from the controlling means, means for locking the carriage against movement whereby a movement of the car produces a relative movement of the car with respect to the carriage, and means for connecting said carriage and said controlling means.
4. The combination with an elevator shaft provided with a door, of an elevator car in said shaft, means for controlling the movement of said car, a movable carriage on said car operably associated with and normally disconnected from the controlling means,

means for locking the carriage against movement whereby a movement of the car produces a relative movement of the car with respect to the carriage, and means for simultaneously connecting said carriage and said controlling means.

5. The combination with an elevator shaft provided with a door, of an elevator car in said shaft, means for controlling the movement of said car, a fixed vertically disposed member in said shaft, a vertically movable carriage on said car operably associated with and normally disconnected from said controlling means and normally out of tight connection with said vertically disposed member, means on the carriage adapted to clamp said member and means for connecting the carriage and the controlling means.

6. The combination with an elevator shaft provided with a door, of an elevator car in said shaft, means for controlling the movement of said car, a fixed vertically disposed member in said shaft, a vertically movable carriage on said car operably associated with and normally disconnected from said controlling means and normally out of tight connection with said vertically disposed member, means on the carriage adapted to clamp said member and means for simultaneously connecting the carriage and the controlling means.

7. The combination with an elevator shaft provided with a door, of an elevator car in said shaft, means for controlling the move-

ment of said car, a fixed vertically disposed member in said shaft, a vertically movable carriage on said car, a lever connected to said carriage, an arm secured to said controlling means, means for clamping said carriage to said member and means for connecting said arm and lever.

8. The combination with an elevator shaft provided with a door, of an elevator car in said shaft, means for controlling the movement of said car, a fixed vertically disposed member in said shaft, a vertically movable carriage on said car, a lever connected to said carriage, a gear on the end of said lever, a gear connected to the controlling means and disposed adjacent said first named gear, means for clamping said carriage to said member, and means for moving said gears into engagement.

9. The combination with an elevator shaft provided with a door, of an elevator car in said shaft, means for controlling the movement of said car, a movable carriage on said car operably associated with and normally disconnected from said means, and mechanism thrown into operation by the opening of the shaft door for locking the carriage against movement and connecting said carriage and said means, whereby a movement of the car produces a movement of the controlling means.

In testimony whereof, I have hereunto set my hand.

WILLIAM H. HARTMAN.
